UNITED STATES PATENT OFFICE.

JOHN MINER AND SILAS MERRICK, OF NEW BRIGHTON, PENNSYLVANIA.

IMPROVEMENT IN RAILROAD-CARS.

Specification forming part of Letters Patent No. 26,282, dated November 29, 1859.

To all whom it may concern:

Be it known that we, JOHN MINER and SILAS MERRICK, both of New Brighton, in the county of Beaver and State of Pennsylvania, have invented certain new and useful Improvements in the Construction of the Bodies of Iron Cars for Railroads, of which the following is a full, clear, and exact description, reference being had to the accompanying drawings, which make part of this specification, and in which—

Figure 1 represents an elevation of a portion of one side of a car embracing our improvements. Fig. 2 represents a horizontal transverse section through one of the panels and uprights of the car at the red line in Fig. 1, showing their method of construction; and Fig. 3 represents a view of the under side of a portion of the bottom of the car.

In the construction of the bodies of railroad-cars it is of primary importance to combine lightness with strength. We have invented a frame for such cars which accomplishes this object in a very complete manner; and our invention consists, first, in constructing the ribs or frame-pieces of railroad-car bodies of two strips of angle-iron, known to the trade as "L-iron," securely riveted to an interposed strip of wood; second, in constructing the panels of the car of single pieces of sheet metal of suitable size and thickness, struck up in the center with an ornamented or plain raised concave from the interior of the car, (or the center may be sunk, and thus made concave to the exterior of the car,) this plate so made being securely riveted round its edges to the L-irons surrounding the space it is designed to fill; third, in combining the said ribs or frame-work with the said panels in the construction of a car, whereby we attain the qualities of strength and lightness in a high degree, combined with beauty of finish and cheapness of construction.

In the accompanying drawings, our improvements are shown as applied to a passenger-car, the frame-work or ribs of which are composed of thin strips or bars *a* of hard wood interposed between two plates *b* of angle-iron, and securely riveted thereto. The edges of the angle-irons and of the wood are made flush with each other in order to facilitate the finishing and upholstering of the car.

The longitudinal beams *A* have their lower edges flush with the bottom of the car, their broad or flanged side being uppermost, and are extended sufficiently beyond the body of the car at each end to support the platforms. The transverse beams *B* are placed with their broadest sides resting upon the longitudinal beams, which they cross at right angles, and the flanges of the two beams are riveted together at each point of intersection. The same form of construction may, if deemed necessary, be applied to the roof and sides of the car; but generally one series of such beams will be found sufficiently strong for all practical purposes for those parts.

The uprights *C* are placed at such distances apart as to leave suitable spaces for windows, and are securely riveted at top and bottom to the side pieces of the frame. The spaces between the uprights are divided into panels by means of strips *c* of angle-iron extending from one upright to another and riveted thereto at each end. The spaces *D* are left for windows, while those above and below are filled with plates *E* of sheet metal struck up at their centers into some ornamental figure, but plain on their edges, which are securely riveted to the uprights *C* and strips *c*. These plates may, if preferred, be made double—that is, two places struck up and placed back to back may be used—and thus the same finish given to the interior as to the exterior of the car. By this method of construction the following among other advantages are attained, viz: Beams of the construction described combine great strength and lightness with a slight degree of elasticity, which latter contributes materially to the smoothness of the motion of a car, and consequently to the comfort of the passengers. The noise produced by the vibration of the car is very much diminished, and a car can be much more cheaply constructed, as our method of construction obviates the necessity of boring or drilling the numberless holes indispensable to the finishing up of a car built entirely of iron.

By the use of panels raised in the center, but having plain edges, riveted to the angle-iron of the frame-work, we are enabled to use lighter material and less of it, and also materially to assist in deadening the sound.

Plates simply corrugated would not answer our purpose, as they cannot be prevented from rattling, and a car in which such plates are used cannot be so strongly or so cheaply constructed as by our method.

Steel might be substituted for iron in the construction of our car; but iron is so much cheaper and possesses ample strength for all practical purposes, that we prefer to use it.

The advantages possessed by an iron car as compared with one constructed of wood are so obvious as scarcely to require mention, the principal ones being those of incombustibility and the absence of splinters, the latter being the chief cause of injury to passengers in case of accidents.

A more detailed description of the construction of our car is deemed unnecessary here, as that is a matter well understood by mechanics and forms no part of the subject-matter of our claims.

We are aware that the use of angle-iron in bridges, houses, and other analogous structures is not new. We are also aware that cor-

rugated plates have likewise been used. These therefore we do not claim; but,

Having thus fully described the construction of our improved railroad-car, what we claim is—

1. In the construction of railroad-cars, inserting strips of wood between the angle-iron which forms the frame-work of the car, in combination with panel-plates formed of a single piece of iron struck up, whether plain or ornamented, substantially as described.

2. Constructing the ribs and frame-work of the car of two strips of L-iron, with a bar of wood interposed, when these irons and the wood are united by rivets, substantially in the manner described.

In testimony whereof we have hereunto subscribed our names.

JOHN MINER.
SILAS MERRICK.
